UNITED STATES PATENT OFFICE.

ARTHUR B. BAKER, OF EAST ORANGE, NEW JERSEY.

FOUR-CYCLE GASOLENE-ENGINE.

1,146,990.

Specification of Letters Patent. Patented July 20, 1915.

Application filed September 10, 1913. Serial No. 789,067.

To all whom it may concern:

Be it known that I, ARTHUR B. BAKER, a citizen of the United States, residing at East Orange, county of Essex, and State of New Jersey, have invented certain new and useful Improvements in Four-Cycle Gasolene-Engines, of which the following is a specification.

The main object of this invention is to provide a multiple-cycle, four-cylinder engine, in which the exhaust valve of each cylinder in turn will be operated by the pressure of the compression or explosion in the cylinder firing immediately after it and next in rotation.

Other important objects and advantages of the invention will appear hereinafter.

In the drawings, Figure 1 is a vertical, longitudinal, sectional view through the engine, the line of the section passing through all of the valves; Fig. 2 is a plan view of the engine; and Fig. 3 a horizontal sectional view taken through the upper part of the engine.

Referring to the various parts by numerals, 1, 2, 3 and 4 designate four cylinders in each of which reciprocates a piston 5. The crank shaft 6 is formed with the two end cranks 7—7 and with the center crank 8. The pistons of cylinders 1 and 4 are connected by pitmen 9 to the crank 7, and the pistons of cylinders 2 and 3 are connected by pitmen 10 to the crank 8. The cranks 7 are precisely alike so that the pistons operated thereby move synchronously and as a pair. It is manifest that the pistons in the cylinders 2 and 3 also move together as a pair so that when the pistons of the cylinders 2 and 3 are at the limit of their inward stroke the pistons connected to the cranks 7 are at the end of their outward stroke, said pistons making their inward stroke when the pistons in cylinders 2 and 3 are making their outward stroke.

Each cylinder is formed with a compression and ignition chamber 11 and with an intake valve 12, an exhaust valve 13, and a pressure-operated piston 100. These valves and the pistons are arranged in suitable openings in the ends of the cylinders. Each intake valve consists of a chambered bushing 14 having a valve seat at its inner end

and shouldered to fit against an annular flange 15 at the inner end of the valve-receiving opening in the cylinder-end. This chambered bushing is held in place by means of a threaded ring 16. The valve 12 is carried by a stem 17 centrally supported in the bushing 14 and provided on its outer end with a head 18, a compression spring 19 being arranged between said head and the outer end of the valve bushing, said spring serving to yieldingly hold the valve 12 to its seat. The exhaust valve 13 also consists of a chambered bushing 20 held in place by a threaded ring 21 and through which the valve stem 22 extends. A head 23 is secured to the outer end of this stem and between said head and the bushing is arranged a spring 24 which holds the exhaust valve to its seat.

The piston or plunger 100 works in a cylinder or bushing 101 fitted in an opening in the head of the cylinder, and held in place in said opening by means of a threaded ring 102, said cylinder being shouldered at its inner end to fit against an annular shoulder 103 formed on the engine cylinder body. The plunger is provided with a stem 104 and at the end of this stem is provided a head 105. The cylinder or bushing 101 is provided with an annular seat 106 for the plunger at its inner end. A spring 107 is placed between the top of the plunger and a cap 108, and serves to hold said plunger normally against said inner seat 106. The heads 23 and 105 of stems 22 and 104 are each laterally apertured to respectively receive valve-operating arms 38, carried by rocking levers 37, pivotally mounted on top of the engine.

The rocking levers 37 are four in number, and they are each so arranged that one of its arms 38 will engage the stem of one of the plungers 100 while the other arm at the other end will be engaged with the stem of one of the exhaust valves, so that the outward movement of the plunger 100 will rock the lever and cause the connected exhaust valve to move inwardly to open position. As will be seen, the arrangement of levers is such that the outward movement of each piston will open the exhaust valve of that one of the cylinders which has just completed its working stroke, and that this

outward movement of the piston is obtained by the pressure of compression or explosion in that one of the cylinders which is the next to be fired. In the drawing, cylinder 5 No. 3 has just been fired and its piston has just commenced the working stroke, and the pressure generated by the explosion has pushed piston 100 outwardly, and this outward movement has caused the exhaust valve 10 in cylinder No. 1 to be opened, this cylinder No. 1 having just completed its working stroke. This action will be repeated in each one of the cylinders in order, to the end that immediately before or after explosion takes 15 place the exhaust valve in the cylinder which is ready to exhaust will be opened.

The explosive mixture is admitted through pipe 26 to the branch pipes 27, these latter pipes communicating with the 20 intake passages 28, these latter passages opening into the intake valve chambers. One intake 28 is in communication with the intake valve chambers of cylinders 1 and 2, the other intake being in communication 25 with the intake valve chambers of cylinders 3 and 4, as shown clearly in Fig. 3. The exhaust valve chambers of cylinders 2 and 3 are in communication with an outlet 29 and the exhaust valve chambers of cylinders 1 30 and 4 are in communication with outlets 30 and 31, respectively, all of these outlets being in communication with a pipe 32.

Each cylinder at its outer end is formed with an annular series of exhaust ports 33 35 which communicate with an exhaust chamber 34, said chamber being in turn in communication with an exhaust pipe. The exhaust chambers 34 of cylinders 1 and 2 are both in communication with an exhaust pipe 35 and the exhaust chambers of cylinders 3 and 4 are in communication with an exhaust pipe 36 so that the exhaust from the cylinders 1 and 2 cannot reach cylinders 3 and 4, and likewise the exhaust from cylinders 3 40 and 4 cannot reach cylinders 1 and 2 so that there will be no possibility of the exhaust from one cylinder igniting the explosive mixture in any one of the other cylinders.

It will be observed from the foregoing 50 that the gist of my invention lies in utilizing a part or modicum of the power developed by the compression or explosion of the charge in each cylinder to automatically assist in exhausting the products of combustion from one of the other cylinders which just completed its working stroke. The preferred manner of doing this is to employ a plunger such as that described and shown 55 and so arranging it that it forms in effect a portion of the wall of the explosion chamber of the cylinder, and in utilizing the outward movement of this plunger to positively open the exhaust valve, but it will be understood that in view of the broad nature 60 of applicant's invention, a great variety of

other devices may be used for carrying out the invention without departing from the spirit thereof.

The plungers 100 are adapted to be forced outwardly by the pressure in the cylinder at 70 the completion of the compression stroke of the pistons 5. The pressure in the cylinder at that time may be due solely to the compression of the piston or it may be due to the explosion of the compressed mixture. It is desirable that the pistons 100 be operated approximately at the time when the piston has completed its compression movement in order that the exhaust valve controlled through the piston 100 will be 80 opened in that cylinder wherein the piston has just begun its exhaust movement. The compression necessary to move the pistons 100 may be nicely regulated by means of the spring 107. It will, of course, be understood 85 that if the pressure produced at the completion of the compression stroke of the piston is not sufficient to move the plunger 100 and thereby open the exhaust valve in another cylinder the pressure produced by 90 the explosion of the mixture will instantly operate the plunger and open the connected exhaust valve. It will, therefore, be seen that it is only necessary that the pressure in the cylinder when the piston has completed 95 its compression stroke be sufficient to move the plunger 100 and it is to be understood that when I refer to the pressure in the cylinder at the time the piston has completed its compression stroke, I mean either the 100 compression pressure or the pressure produced by exploding the gas mixture. It is immaterial how the pressure is produced provided it is present in the cylinder at the time when the piston is at the inner end of 105 the cylinder and has completed or about completed its compression movement.

It will be understood also that the present invention is not necessarily confined to the type of engine described, in which the main exhaust takes place at the outer ends of the cylinders, but in case the invention is applied to that type in which the entire exhaust will take place through the automatically operated exhaust valves 13, it is 110 probable that a type of valve different from that illustrated will need to be employed, in view of the heavy pressure that would have to be overcome in order to open the valves. For instance, in such case I might employ a 115 rotary valve and connect the same up to the pressure piston 100, so that the outward movement of the piston would rotate or oscillate the valve to exhaust position. Again, I might provide a preliminary or 120 pilot valve which would open preliminarily to the main valve and thus relieve the pressure sufficiently to permit the main valve to be readily opened.

By providing the supplemental exhaust 130

through the ports 33 the pressure in the cylinders is greatly reduced, thereby permitting the ready operation of the exhaust valves through the pressure of compression or explosion. It is also manifest that by providing means for exhausting the burned gases at both ends of each cylinder a thorough cleaning out of each cylinder is secured.

- 10 From the foregoing it is manifest that I combine in this engine the advantages of both the two-cycle engine and the four-cycle engine. The engine may be started by rotating the crank shaft in either direction. 15 There are no mechanical connections between the crank shaft and the valves so that the engine is reversible. I provide an engine having an exhaust at both ends of each cylinder, thereby securing a very complete 20 expulsion of the burned gases and insuring a complete charge of fresh explosive mixture. By operating both the intake and exhaust valve by means of the pressure of compression or explosion, I avoid the use of all 25 valve operating cams and rods. I have combined the simplicity of a two-cycle engine with the efficiency of a four-cycle engine.

It will be observed that in view of the fact that the springs 24 of the exhaust valves 30 merely augment the action of the springs 107 of the plungers, it may be possible to do away with one or the other of these springs. It will be observed also that it is probably not material whether the pistons 100 be actuated by the pressure of compression or the 35 pressure of explosion, but, should the springs 107 be adjusted as to tension so that the pressure of compression will actuate the pistons, it will be seen that the explosion which 40 subsequently follows will render the action of the pistons more certain in that, should they stick, the pressure of the explosion will cause them to be actuated.

It may be desirable to so adjust the tension of springs 107 that the pistons 100 will 45 be actuated by pressure of compression alone, so that by the time the shock of the explosion takes place, the pistons will have been pressed outwardly far enough to be solidly 50 seated against the springs, in which case all danger of crystallizing the metal of the springs by the severe and repeated shocks of explosion will be avoided. Should it be desirable to actuate the pistons by explosion 55 pressure, it may be necessary to provide means whereby the severe shocks of explosion will be prevented from injuring the springs by breaking or crystallizing them. One way of doing this would be to choke 60 the passage of gas from the explosion chamber into the piston chamber. In the structure illustrated, this choking action may be accomplished by the annular flange 106, but, should this annular flange be insufficient to 65 sufficiently choke down the action of the gas

on the piston, this flange may be increased in diameter to any desired extent; and, should it be desired from time to time to vary the area of this choked passage, it will be observed that I may readily provide the same 70 with means to manually vary the area from time to time.

Having thus described my invention, what I claim is:

1. A multiple-cylinder four-cycle internal combustion engine comprising a multiplicity of cylinders, an inlet valve and an exhaust valve for each cylinder, a movable piston in each cylinder, a movable part forming a portion of the wall of the explosion chamber and means connected to each of said movable parts whereby the pressure in each cylinder at the completion of the compression stroke of the piston will open the exhaust valve of one of the other cylinders. 75 80 85

2. A multiple-cylinder four-cycle internal combustion engine comprising a multiplicity of cylinders, an inlet valve and an exhaust valve for each cylinder, a movable piston in each cylinder, a movable plunger forming a portion of the wall of the explosion chamber and means connected to each of said movable plungers whereby the pressure in each cylinder at the completion of the compression stroke of the piston will open 90 95 the exhaust valve of one of the other cylinders.

3. A multiple-cylinder four-cycle internal combustion engine comprising a multiplicity of cylinders, an inlet valve and an exhaust valve for each cylinder, a movable piston in each cylinder, movable means connected to each cylinder and exposed to the pressure therein and means connected to each of said movable means and to an exhaust valve of 100 105 one of the other cylinders, whereby the pressure in each cylinder at the completion of the compression stroke of the piston will open said connected exhaust valve.

4. A multiple-cylinder four-cycle internal combustion engine comprising a multiplicity of cylinders, an inlet valve and an exhaust valve for each cylinder, a movable piston in each cylinder, a movable plunger for each cylinder and exposed to the pressure in said 110 cylinder, means connecting each plunger to the exhaust valve of one of the other cylinders, a spring for normally forcing each of said plungers inwardly, whereby the pressure in each cylinder at the completion of 115 120 the compression stroke of the piston will open the exhaust valve of another cylinder.

5. A multiple-cylinder four-cycle internal combustion engine comprising a multiplicity of cylinders, an inlet valve and an exhaust valve for each cylinder, a movable piston in each cylinder, a movable plunger for each cylinder and exposed to the pressure in said cylinder, mechanical means connecting each plunger to the exhaust valve of one of the 125 130

other cylinders, a spring for normally forcing each of said plungers inwardly, whereby the pressure in each cylinder at the completion of the compression stroke of the piston will open the exhaust valve of another cylinder.

In testimony whereof I hereunto affix my signature in the presence of two witnesses.

ARTHUR B. BAKER.
